UNITED STATES PATENT OFFICE.

ROBERT ALFRED JACQUAT, OF PARIS, FRANCE.

HAIR-CUTTING APPARATUS.

1,333,315.

Specification of Letters Patent.

Patented Mar. 9, 1920.

Application filed May 28, 1919. Serial No. 300,332.

To all whom it may concern:

Be it known that I, ROBERT ALFRED JACQUAT, citizen of the Republic of France, and resident of Paris, France, postoffice address 137 Rue de Rennes, have invented a new and useful Hair-Cutting Apparatus, which improvements are fully set forth in the following specification.

The present invention relates to an implement enabling a person to cut his own hair.

This implement is composed essentially of an adjustable comb which is fitted in an improved manner to an ordinary razor blade. The razor thus fitted is passed along the hair and cuts it, the depth of the cut being determined exactly by regulating the comb in relation to the razor blade.

The razor fitted with the attachment in question can also be used for the beard and constitutes a safety-razor.

The invention is illustrated by way of example in the accompanying drawing.

Figure 1 shows the attachment fitted on to a razor blade.

Fig. 2 is a view of the attachment as it appears alone.

The improved attachment consists of a comb-like part *a* carrying two supports *b* which project perpendicularly from the back of the comb and around each of which is wound a helical spring *c*. At the threaded outer end of each support *b* a nut *d* is applied. Each support *b* is formed from, and is in one piece with the flat metal strip forming the body of the comb *a* itself.

Two spring clips *e* are provided and may be made of the metal which falls away when the device is being shaped by stamping. These clips are adapted to straddle the back of the blade, and are suitably bent and rounded off so that they slip easily on said blade.

One leg of each clip *e* has two slits *g* which are disposed in spaced, parallel relation so as to leave a narrow strip or bridge between them, beneath which bridge, as is shown in Fig. 1—the corresponding support *b* is passed. This arrangement serves to hold the comb tightly pressed against the razor blade. After the two separate parts, (the comb and the razor) have thus been firmly clamped together the nuts *d* are screwed into position.

It will be seen that with this form of mounting and with the nuts *d* it is possible to regulate the position of the toothed part

of the comb *a* in relation to the edge of the razor blade *f*. The springs *c* continually tend to press the comb *a* down farther away from the clips *e*.

It will be readily understood that the two clips *e* could be held together or be in one piece by having a back in common, the said back fitting on to the back on the razor.

Having now particularly described and ascertained the nature of my said invention and in what manner the same is to be performed, I declare that what I claim is:

1. An adjustable attachment for razor blades, comprising a comb adapted to rest against one face of the blade and having rigidly connected to it a pair of spaced supports which project laterally from the back of the comb and have their free ends threaded; a pair of spaced U-shaped spring clips adapted to straddle the back of the blade, one leg of each clip being provided with a pair of parallel slits and with a bridge between them beneath which the adjacent support is inserted, whereby the comb is yieldingly pressed against the blade by the clips; and a pair of nuts mounted on the threaded portions of said supports to adjust the comb with relation to the blade edge.

2. An adjustable attachment for razor blades, comprising a comb adapted to rest against one face of the blade and having rigidly connected to it a pair of spaced supports which project laterally from the back of the comb and have their free ends threaded; a pair of spaced, U-shaped spring clips adapted to straddle the back of the blade, one leg of each clip being provided with a pair of parallel slits and with a bridge between them beneath which the adjacent support is inserted, whereby the comb is yieldingly pressed against the blade by the clips; a pair of nuts mounted on the threaded portions of said supports to adjust the comb with relation to the blade edge; and an expandable coil spring encircling each support and bearing at opposite ends against the back of the comb and the free edge of the adjacent clip leg, said springs tending to press the comb forwardly toward the blade edge.

In testimony whereof I have signed this specification in the presence of two subscribing witnesses.

ROBERT ALFRED JACQUAT.
